APPARATUS FOR SINKING TUBULAR WORK
PIECES

Bryant Bannister, Mount Lebanon, Pa.

Application March 14, 1933, Serial No. 660,718

1 Claim. (Cl. 80—13)

This invention relates to the manufacture of seamless pipes and tubes from cast or rolled rounds, and particularly to that procedure in such operations where a tubular blank is materially reduced in diameter and elongated, which is known in the art as "sinking" in contrast to light reductions known as "sizing".

In the manufacture of small diameter "merchant pipe" by the seamless process and in the preparation of tubular blanks for cold drawing, particularly that process known as cross-rolling, it is desirable to first produce a seamless tubular blank having a diameter larger than that of the finished pipe, and to reduce this diameter and control the wall thickness by a subsequent operation, which can be carried on at a reasonably high speed and low cost.

The usual sinking method employed to make large reductions in the diameter of a tubular blank consists in passing the blank between a series of grooved power driven rolls arranged in pairs to form a circular pass, each pass having a smaller diameter than the preceding one. Reducing, or sinking, mills of this type are costly to operate because of the high cost of maintenance and the difficulty in controlling wall thickness of the product. In addition, the loss occasioned by cropping unfit ends is high.

The method employed in my invention consists in feeding the tubular blank to be reduced between a pair of cone shaped power driven work rolls so arranged that their axes lie in parallel planes, but some distance apart. The axis of the tubular blank lies in a plane parallel to these two planes and substantially midway between them. The projections of the main roll axes upon the plane containing the axis of the tubular blank make equal angles with the axis of the blank. Each roll is driven by a suitable power source at substantially the same rotative speed. These rolls also have the same ratio of expansion or taper as the tube while passing through the mill. This arrangement provides that the peripheral velocity of the work rolls bears a substantially uniform ratio to the peripheral velocity of the work-piece for all transverse sections through the converging portion of the pass and rolls.

Positioned above and below the tube being acted upon and intermediate the two main rolls are two power driven guide rolls of large diameter. These guide rolls contact with the tube being reduced, and in conjunction with the main rolls form the pass shown in the drawings. The large diameter of the guide rolls provides a long arc of contact and consequently a moderate angle of

reduction; that is to say, the conical section of the tube being reduced is of considerable length and the included or flow angles between guide rolls is substantially the same as the angle included by the adjacent faces of the main rolls. These guide disks are driven at approximately equal speeds and at a peripheral speed substantially greater than the speed of the main rolls, and consequently greatly in excess of the longitudinal travel of the pipe or tube.

In a preferred embodiment of my invention a floating mandrel slightly less in diameter than the inside diameter of the reduced tube is used. It is obvious that if the tube is reduced in diameter the wall will increase in thickness, although the action of the guide rolls may tend to keep this thickening effect below that corresponding to the reduction in diameter. The diameter is reduced and the wall thickened until the metal of the tube is in contact with both the main rolls and the floating mandrel. From the gorge or narrowest portion of the pass to the outlet, the metal is reduced in wall thickness simultaneously with the reduction in diameter. In this portion of the pass the metal would be forced into a decidedly oval cross-section if not restrained by the guide rolls, but owing to the restraining effect of the guide rolls and the high peripheral speed of these rolls in the direction of tube travel this potential ovality is turned into length. The tube, after reduction, may thus have the same wall thickness as the large diameter tube entering the mill, and will have a length greater than that of the entering tube in proportion to the cross-sectional area of the entering tube as compared to that of the tube as it leaves the mill.

In a modified form of my invention a tapered plug is introduced between the rolls and held in position by a supporting bar which is free to rotate with the tube but restrained from moving forward with the tube. In this case it is preferable to provide a plug having the same taper as that defined by the main rolls, so that the wall thickness of the tube being reduced remains substantially constant, although if desired a slight reduction in wall thickness can be made as the diameter is reduced.

If the guide roll speed is maintained sufficiently high there will be little tendency for the metal to bulge between various roll contacts, but it may be desirable to introduce stationary guiding surfaces for a short distance at the large end of the reducing section simply to restrain such bulging.

One object of my invention is to provide means whereby a tube is substantially reduced in di-

ameter and elongated without any substantial change in wall thickness.

A further object is the provision of a novel apparatus whereby the work-piece is elongated largely because of a reduction in diameter.

A still further object is the provision of a novel apparatus for reducing or sinking the tube diameter wherein the cross-sectional area of the tube is allowed to remain substantially uniform for the first portion of the pass and is then reduced to effect elongation.

A still further object is the provision of novel means and apparatus for reducing or sinking the diameter of a tube by helical rolling without subjecting the tube being reduced to twisting due to improper surface speed relations between the main rolls and work-piece.

These and further objects of the invention will appear after referring to the drawings, in which:

20 Figure 1 is an end elevation of the apparatus of my invention.

Figure 2 is a plan view thereof.

Figure 3 is a transverse section taken along the lines III—III of Figure 2.

25 Figure 4 is a transverse section taken along the lines IV—IV of Figure 2.

Figure 5 is a transverse section taken on the line V—V of Figure 2.

30 Figure 6 is a composite view disclosing the relationship of one work roll to one of the guide rolls which is shown, together with a portion of the billet, in a plane substantially 90° from its true position in the mill.

Figure 7 is a view similar to Figure 3, in which 35 I have disclosed a modified form of my invention.

Referring more particularly to the drawings, in Figure 1 the numeral 2 indicates a pair of work rolls disposed on opposite sides of the work-piece 4 and contacting with it, one above the horizontal center line of the work-piece and one below. The guide rolls 3 are disposed between the work rolls and contact the work-piece a greater distance from its axis than to the work rolls. This arrangement allows a slight ovality which is particularly necessary near the "gorge" or most constricted portion of the pass, to prevent the work-piece from binding on the mandrel. The guide rolls are driven by suitable means and have a peripheral velocity towards the outlet of the pass greatly in excess of the longitudinal travel of the piece out of the pass. A mandrel 5 is positioned within the hollow work-piece.

Referring to Figure 2, which is a plan of the apparatus illustrated in Figure 1, the pass formed by the work rolls 2 and guide rolls 3 has a converging portion 2^a to the "gorge" point of the pass. From the "gorge" point and extending slightly in the direction of the outlet end there is provided a substantially flat or parallel work surface 2^b, and from this point through the outlet end of the pass there is provided a diverging portion 2^c.

The diameter of the work-piece in a vertical plane is limited by the guide rolls 3 so that in any transverse plane it is slightly greater than the horizontal diameter. In other words, the work-piece is slightly oval in section. The decrease in diameter of the work rolls is at the same rate as the decrease in diameter of the work-piece, thus the angular or surface velocity of the work rolls bears a substantially uniform ratio to the surface speed of the work-piece at any transverse section of work-piece and work roll. If slip or relative movement between roll and work-piece is neglected the surface speeds would be

identical at any section. This relationship of speeds avoids the tendency of the rolls to impart to the work-piece a greater angular velocity at one section than another, or the tendency to twist the work-piece is avoided.

5 In Figure 6 one work roll 2 is shown contacting with the work-piece 4, shown in section, and the mid-section of one guide roll 3 also contacting with the work-piece 4. This view of the guide roll and work-piece is shown rotated about the axis of the work-piece 90 degrees from its true position. As shown, the work-piece first contacts with the work rolls on line A—A and is rotated and advanced helically into the pass. As the horizontal distance between the work rolls decreases the work-piece assumes an oval section and contacts the guide rolls at point a. As the work-piece proceeds further into the pass the horizontal width continues to decrease but the guide rolls, due to their high velocity in the direction of the work-piece travel and contact with it, limit the vertical diameter of the oval by spinning the metal into reduced diameter.

10 A portion of the metal of the work-piece is displaced in a longitudinal direction but the greater part of the displacement goes to increase wall thickness. Thus the work-piece is reduced in diameter with little change in cross-sectional area. When section B—B is reached the work-piece contacts the mandrel 4 and in traversing 15 a helical path to section C—C of the pass the wall thickness is reduced to that desired in the reduced tube. As the metal is displaced between the work rolls 2 and the mandrel 5 there is a natural tendency for it to flow radially to increase 20 the diameter of the work-piece. The tendency to flow radially produces great pressure against the guide rolls and because of their high velocity towards the outlet of the pass, the metal is diverted from radial to longitudinal flow and the work-piece is lengthened. This restraining effect of the guide rolls 3 is, of course, assisted by stationary guides 3^a, which only contact the work-piece in the converging portion 2^a of the work 25 roll pass.

40 The faces of the work rolls from section C—C to section D—D are parallel to the mandrel and reel out inequalities that remain in the wall of the work-piece. From section D—D to section 45 E—E the faces of the work rolls diverge, allowing the horizontal diameter of the work-piece to increase with a corresponding decrease in vertical diameter. At section E—E the horizontal growth in diameter just equals the vertical shrinkage and the work-piece assumes a circular section.

50 Figure 7 shows a modified form of my invention where a plug 6 is substituted for mandrel 5. Plug 6 is supported on a bar 7 which is free to rotate but is restrained from longitudinal movement. The contour and position of plug 6 is such that a 55 metal pass is formed in conjunction with work rolls 2 and guide rolls 3 varying in width from the thickness of the work-piece entering the pass to some reduced width, or the pass may be uniform in width so that the wall thickness of the work-piece is maintained uniform throughout the pass. The action in the pass is the same as that described for Figure 6 except that the wall thickness of the work-piece is maintained or reduced and there is a gradual reduction in cross-sectional 60 area of the work-piece instead of a more concentrated reduction as described for Figure 6.

65 The term "sinking" as used throughout the specification and claim is intended to define an operation wherein the tube diameter is materially 70 75

reduced, as contrasted with slight reductions in diameter commonly called "sizing".

While I have shown and described several specific embodiments of my invention, it will be understood that I do not wish to be limited thereto, since various modifications may be made without departing from the scope of my invention, as defined in the following claim.

I claim:

10. Apparatus for sinking tubular work pieces comprising two metal working rolls and a mandrel defining a pass, said rolls and mandrel being con-

structed and arranged to provide a reducing pass having a convergent portion co-extensive with the major part of the length of said rolls, a substantially short reeling portion, and a divergent portion, in combination with a power-actuated guide roll for guiding and assisting the work piece through the outlet end of the pass, said guide roll having its contact surface nearest the axis of the workpiece positioned adjacent said reeling portion.
